CLAIM

The ornamental design for a weatherproof multipurpose enclosure, as shown and described herein.

DESCRIPTION

FIG. 1 is a perspective view of a weatherproof multipurpose enclosure embodying our design;

FIG. 2 is a top plan view thereof;

FIG. 3 is right-side elevation thereof; and,

FIG. 4 is a front elevation view thereof.

The broken lines shown in the drawings represent portions of the weatherproof multipurpose enclosure that form no part of the claimed design.
